(57) **CLAIM**

I claim a headrail for covering for architectural openings, as shown and described.

DESCRIPTION

FIG. 1 is an isometric of the headrail of the present invention looking at the front.

FIG. 2 is a rear isometric similar to FIG. 1.

FIG. 3 is a top plan view.

FIG. 4 is a front elevation.

FIG. 5 is a bottom plan view.

FIG. 6 is a left side elevation of the headrail as shown in FIG. 7.

FIG. 7 is a rear elevation.

FIG. 8 is a right side elevation of the headrail as shown in FIG. 7.

FIG. 9 is a front isometric of a first alternative embodiment to the headrail shown in FIG. 1 with the front of the headrail having a fabric covering thereon.

FIG. 10 is a rear isometric similar to FIG. 9.

FIG. 11 is a top plan view of the headrail of FIG. 9.

FIG. 12 is a front elevation of the headrail of FIG. 9.

FIG. 13 is a bottom plan view of the headrail of FIG. 9.

FIG. 14 is a left side elevation of the headrail as shown in FIG. 15.

FIG. 15 is a rear elevation of the headrail of FIG. 9; and,

FIG. 16 is a right elevation of the headrail as shown in FIG. 15.
